UNITED STATES PATENT OFFICE.

GEORGE H. RENNICK, OF INDIANAPOLIS, INDIANA.

DESIGN FOR A MILITARY-BAR RIBBON.

56,625.

Specification for Design.

Patented Nov. 16, 1920.

Application filed April 6, 1920. Serial No. 371,786. Term of patent 14 years.

To all whom it may concern:

Be it known that I, GEORGE H. RENNICK, a citizen of the United States, residing at Meridian Life Building, in the city of Indianapolis, county of Marion, State of Indiana, have invented a new, original, and ornamental Design for a Military-Bar Ribbon, of which the following is a specification, reference being had to the accompanying drawing, forming part thereof.

The figure is a plan view of a military bar ribbon, showing my new design. The lining on the drawing indicates the respective colors as shown, dark drab, purple, light blue, green, yellow, crimson, dark blue, crimson, yellow, green, light blue, purple, and light drab.

I claim:

The ornamental design for a military bar ribbon, as shown.

GEORGE H. RENNICK.
